UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 17,478, dated July 26, 1887.

Application filed April 12, 1887. Serial No. 231,554. Term of patent 14 years.

To all whom it may concern:

Be it known that I, GEORGE W. BLAIR, of Pittsburgh, in the county of Allegheny and State of Pennsylvania, have invented a new and original Design for Lamp-Chimneys; and I do hereby declare the following to be a full, clear, and exact description thereof.

My design consists in a lamp-chimney ornamented substantially as represented in the accompanying drawings, wherein—

Figure 1 is an elevation of a lamp-chimney showing the design, and Fig. 2 is an enlarged view of a portion thereof.

The characteristic features of the design consist in the configuration and ornamentation of a band, *b*, around the outside of the top of the chimney *a*. The band is ornamented with a number of parallel rows of raised or sunken diamonds or prismatic figures, and the shape of the chimney-top is such that the portion on which is the band tapers or gradually lessens in diameter toward the extreme top.

Otherwise than as above stated, the chimney is of the usual form.

The prismatic figures on the inclined or tapering band or zone around the chimney-top refract light and produce an ornamental effect.

I claim—

The design for lamp-chimneys, consisting in a lamp-chimney having a band extending around the outside of the top, said band being provided with diamond-shaped ornamentations arranged contiguously in parallel rows, substantially as shown and described.

In testimony whereof I have hereunto set my hand this 11th day of April, A. D. 1887.

GEORGE W. BLAIR.
